(57) **CLAIM**

The ornamental design for a display screen or portion thereof with animated graphical user interface as shown and described.

DESCRIPTION

FIG. 1 is a front view of a display screen or portion thereof with animated graphical user interface showing the first image in a sequence of our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof;

FIG. 12 is another view of FIG. 1, but shown with additional broken line subject matter;

FIG. 13 is another view of FIG. 2, but shown with additional broken line subject matter;

FIG. 14 is another view of FIG. 3, but shown with additional broken line subject matter;

FIG. 15 is another view of FIG. 4, but shown with additional broken line subject matter;

FIG. 16 is another view of FIG. 5, but shown with additional broken line subject matter;

FIG. 17 is another view of FIG. 6, but shown with additional broken line subject matter;

FIG. 18 is another view of FIG. 7, but shown with additional broken line subject matter;

(Continued)

FIG. 19 is another view of FIG. 8, but shown with additional broken line subject matter;

FIG. 20 is another view of FIG. 9, but shown with additional broken line subject matter;

FIG. 21 is another view of FIG. 10, but shown with additional broken line subject matter; and,

FIG. 22 is another view of FIG. 11, but shown with additional broken line subject matter.

The appearance of the animated graphical user interface

sequentially transitions between the images shown in FIGS. 1-11 and 12-22. The process or period in which one image transitions to another forms no part of the claimed design. The dot-dash broken line illustrates a display screen or portion thereof and forms no part of the claimed design. The even-dash broken lines in FIGS. 12-22 illustrate portions of the animated graphical user interface that form no part of the claimed design.
